ATTORNEY

UNITED STATES PATENT OFFICE.

VICTOR WILOUGHBY, OF RIDGEWOOD, NEW JERSEY, ASSIGNOR TO AMERICAN CAR AND FOUL DRY COMPANY, OF NEW YORK, N. Y., A CORPORATION OF NEW JERSEY.

CAM SHEAVE AND SUPPORT FOR BRAKES.

Application filed January 17, 1924. Serial No. 688,782.

To all whom it may concern:

Be it known that I, VICTOR WILLOUGHBY, residing at Ridgewood, Bergen County, New Jersey, and being a citizen of the United States, have invented certain new and useful Improvements in a Cam Sheave and Support for Brakes, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Fig. 1 is a fragmentary end elevation of a hopper car showing a cam sheave and support constructed in accordance with this invention applied thereto, the brake being shown in the released position;

Fig. 2 is a vertical section taken on the line 2—2 of Fig. 1;

Fig. 3 is a view in elevation showing the position of the cam sheave with the car brakes partially applied;

Fig. 4 is a horizontal section taken on the line 4—4 of Fig. 1;

Fig. 5 is an end elevation similar to Fig. 1 showing a modified construction of the cam sheave supporting means;

Fig. 6 is a vertical section taken on the line 6—6 of Fig. 5; and

Fig. 7 is a horizontal section taken on the line 7—7 of Fig. 5.

40 It is an object of this invention to provide an improved power multiplying cam sheave and support for the hand brakes of railway cars. It is also an object of this invention to provide a support for the cam sheave of such construction that it may be secured beneath the brake step and which is provided with bracing means which serve as a step for the brake mast.

With these and other objects in view the invention is shown in Figs. 1 to 4 inclusive, as applied to a hopper car having an end

sheet 1 and a slope floor sheet 2. Secured to the plates 1 and 2 at their meeting edges by gusset plates 3 are vertical angles 4 which are connected by gusset plates 5 to the flanged plate 6 which is secured to the upper flange of the end sill 7. Secured to the angle 4 is a member 8 to which a brake lever 9 is pivotally secured as at 10 and to which is connected a brake cylinder rod 11 and a 60 brake rod 12.

Secured to the end sheet 1 are brackets 13 which support a brake step 14 having secured to its underside an inverted U-shaped member 15 which has its web 16 riveted to the underside of the brake step 14 and its inner side 17 secured to the end sheet 1 and floor sheet 2 by the rivets 18 which secure the adjacent gusset plate 3 to the end and floor sheets. The inner side 17 of the member 15, and the outer side 18, are both provided with openings to receive a pin 19 having a head at one end and an opening to receive a cotter pin at the other end, and upon which is mounted, between the sides 17 and 18, a cam sheave 20 which has a channeled substantially semi-circular portion 21 about which extends a chain 22 which lies in the channel and has one of its ends connected to the sheave at an end of the channel at 22', and its other end connected to a brake mast 23. The brake mast 23 has its lower end reduced as at 24, and engaging in an opening in a brake mast step 25 which has its ends fastened to the sides 17 and 18 of the member 15, and provided with openings 70

75 to receive the pin 19. The step 25 thus serves to support the lower end of the brake mast 23 and to connect the opposite sides of the member 15, thereby bracing the member 15 against separation of the sides 17 and 18, and serving also as a strut between the member 15 and the brake mast. The brake mast 23 is mounted in the brake step 14 and in a guide collar 26 secured to the upper end 80 of the end sheet 1, and is provided with a pawl 27, ratchet 28 and hand wheel 29 in the usual manner.

To the side of the portion 21 of the cam sheave 20 is secured a lug 30 to which a chain 31 is connected, the chain 31 extending around a roller 32 in a bracket 33 formed 85

in one of the gusset plates 5 and connected to the brake lever 9. As shown in Fig. 1, the chain 31 extends directly from the lug 30 to the roller 32 when the brake is in the released position, and upon the operation of the sheave to apply the brakes the chain 31 will be shifted by the lug 30 into engagement, as shown in Fig. 3, with a drum 34 formed at the hub of the cam sheave, the chain being wrapped about the drum as the brakes are applied. It will be noted that while the cam sheave 20 is shifted from the position shown in Fig. 1 to the position shown in Fig. 3 in applying the brakes, the effective radius through which the chain 22 applies power to the cam sheave 20 gradually increases to a maximum, whereupon it remains constant and the effective radius through which the cam sheave 20 applies power to the chain 31 gradually decreases to a minimum whereupon it remains constant, a construction which provides maximum speed in bringing the brake shoes into contact with the wheels and maximum power thereafter.

25. In the modification shown in Figs. 5 to 7, the invention is shown applied to a higher car having an end sheet 50 and a slope floor sheet 51, the end sheet 50 being connected by a Z-bar member 52 to the end sill 53. To the end sheet 50 are secured brackets 54 which support a brake step 55 in which is mounted the usual brake mast 56. Secured to the step 55 by the bolts 57 is an inverted U-shaped member 58 having its web 59 in engagement with the underside of the step and its inner side 60 secured to the Z-bar member 52 by the rivets 61. Both the inner side 60 and the outer side 62 of the U-shaped member 58 are provided with openings to receive a pin 63 on which is mounted a cam sheave 64 of similar construction to the cam sheave shown in Figs. 1 to 4. Extending across below the bottom edges of the sides 60 and 62 of the member 58 is a flanged plate 65 having its flanges secured to the bottom ends of the sides 60 and 62, and provided with an opening to receive the reduced lower end 66 of the brake mast 56. In this construction as in the construction shown in Figs. 1 to 4, the brake mast is connected by a chain 67 which is wrapped about the semi-circular portion of the cam sheave 64 and secured thereto as at 68, while the semi-circular portion of the cam sheave 64 is provided with a lug 69 to which is secured a chain 70 which passes around a roller 71 mounted in a bracket 72 secured to the end sill 53 and is connected to a brake lever 73. In this construction the plate 65 serves to prevent spreading of the sides of the U-shaped member 58, as a step for the brake mast 56 and as a strut between the brake mast 56 and the U-shaped member 58.

What is claimed is:

1. In a car, a brake step, a power multiplying device operatively connected to the brake lever, means connecting said power multiplying device and said brake step, a brake mast and a brake mast step carried by said connecting means.
2. In a car, a brake step, a member secured to said brake step, a power multiplying device mounted in said member and operatively connected to the brake lever, a 75 brake mast operatively connected to said power multiplying device and a brake mast step forming a strut between said member and said brake mast.
3. In a car, a brake step, a power multiplying device operatively connected to the brake lever, a U-shaped member secured to said brake step and carrying said power multiplying device, a brake mast operatively connected to said power multiplying device 80 and a brake mast step carried by said U-shaped member.
4. In a car, a brake step, an inverted U-shaped member secured to said step, a power multiplying device mounted in said U-shaped member and operatively connected to the brake lever, a brake mast operatively connected to said power multiplying device 85 and a brake mast step connecting the sides of said U-shaped member.
5. In a car, a brake step, a U-shaped member secured to said brake step, a cam sheave mounted in said member operatively connected to the brake lever, a brake mast operatively connected to said cam sheave 100 and a brake mast step connecting the sides of said U-shaped member and forming a strut between said U-shaped member and said brake mast.
6. In a car brake, a cam sheave operatively connected to the brake lever, a brake mast operatively connected to said cam sheave, a U-shaped member supporting said cam sheave and a brake mast step connecting the sides of said U-shaped member. 105
7. In a car brake, a power multiplying device operatively connected to the brake lever, a brake mast operatively connected to said power multiplying device, an inverted U-shaped member supporting said power 115 multiplying device and means bracing said supporting means and supporting said brake mast.
8. In a car brake, a cam sheave operatively connected to the brake lever, a brake mast operatively connected to said sheave, an inverted U-shaped member supporting said sheave and means bracing said supporting member and supporting said brake mast adapted to serve as a strut between said supporting member and brake mast. 120
9. In a car brake, a cam sheave operatively connected to the brake lever, a brake 125

mast operatively connected to the cam sheave, an inverted U-shaped member supporting said sheave and a strut between said brake mast and U-shaped member supporting said brake mast.

10. In a car brake, a cam sheave operatively connected to the brake lever, a brake mast operatively connected to the cam sheave, an inverted U-shaped member sup-

porting said cam sheave and means supporting said brake mast carried by said U-shaped member.

In witness whereof I have hereunto set my hand in the presence of two witnesses.

VICTOR WILLOUGHBY.
